UNITED STATES PATENT OFFICE.

ERSKINE L. BABCOCK, OF CUYAHOGA FALLS, OHIO, ASSIGNOR TO THE FALLS RIVER COMPANY, OF SAME PLACE.

CLUTCH.

SPECIFICATION forming part of Letters Patent No. 373,425, dated November 22, 1887.

Application filed May 10, 1887. Serial No. 237,674. (No model.)

To all whom it may concern:

Be it known that I, ERSKINE L. BABCOCK, of Cuyahoga Falls, Summit county, State of Ohio, have invented a new and useful Improvement in Clutches, of which the following is a specification.

The object of my invention is to provide a clutching mechanism by which the motions of a shaft may be communicated at pleasure to a pulley, drum, or the like by means which are powerful, simple, and inexpensive.

It consists in locating a friction-shoe in proper position to bear against a ring on the pulley or the mechanism to be turned, and mounting the shoe upon a reciprocating piece which is in turn supported in guideways on an arm connected with the shaft, and which is actuated by a lever or levers connected with a shifter.

20 In the drawings I have represented the form of mechanism which I at present believe to be the best for the purpose of carrying out my invention.

Figure 1 is a central longitudinal section through the axis of a pulley having my mechanism attached. Fig. 2 is a transverse section of the same through the line 1-1, Fig. 1.

a is the shaft.

b b' are respectively the rim and hub of a pulley which is free to revolve upon the shaft, but is held in place by the collar *c* on one side and the collar *d* on the other side.

e is a ring connected with the pulley.

f is the shoe, which may be faced with a friction-surface, of wood or other suitable material, to bear against the interior side of the ring *e*. The shoe *f* is mounted upon the extremity of a piece, *g*, which is provided at its inner extremity with a set-screw, *h*. The piece

40 *g* is connected with the shaft *a* through the arm *i*, projecting radially from the collar *d*, the connections being such that the piece *g* is free to reciprocate radially to and from the shaft. Connected with the shaft is also the

45 lever *j*, which is provided with a cam-surface, *k*, and which is so pivoted as to cause this cam-surface to operate upon the head of the set-screw *h* as said lever is moved. The arm of said lever *j* is pivoted at its outer extremity

50 to a link, *l*, which is also pivoted to the shifter

m, as shown in the drawings. A spring, *n*, is so arranged as to produce an inward pressure upon the piece *g*, which has a tendency to disengage the friction-surface of the shoe *f* from the ring *e* of the pulley, so that when the piece *g* is not forced outward by the action of the lever *j* the friction-surfaces will be out of contact.

In construction I find it convenient to make the piece *g* in the form of a rod, which, if 60 cylindrical, may be prevented from revolving by a set-screw, *o*, which fits in a groove on the piece *g*. I also find it convenient in construction to employ the flanges *p p'*, which are perforated, so as to form guideways for the piece 65 *g*. Thus, also, a bearing-surface is afforded by the surface of the flange *p* for the spring *n*, which spring may be provided with another bearing-surface by means of the flange *q*, connected with the piece *g*.

The lever *j* is shown as pivotally connected to the shaft at *r* on one side of the arm *i*, and is pivotally connected to the link *l* on the opposite side thereof, a hole being cut through the arm *i* sufficient to enable the lever to operate in this position. It will also be observed that in the drawings I have represented four arms *i*, each of which is provided with a duplicate of the mechanism which I have described. The number of said arms is immaterial.

The operation of my contrivance may be described as follows: The drawings represent the friction-surfaces as being forced into contact with each other, where they are substantially locked by reason of the fact that the 85 jointed link *l* has passed slightly beyond the vertical. To release the friction-surfaces the shifter *m* is moved slightly to the right, Fig. 1, thereby lowering the cam-surface on the lever *j*, and thus permitting the spring *n* to 90 throw the piece *g* inwardly, so as to separate the friction-surfaces. The presence of the set-screw *h* enables the taking up of the wear of the parts.

I have described the best form known to 95 me at present for utilizing my invention; but obviously the construction and mechanism described may be changed in various particulars without departing from the scope of my invention.

I claim—

In combination, the pulley, the ring *e*, concentric about the shaft, the collar *d*, secured to the shaft and provided with arm *i*, having flanges *p* and *p'*, the piece *g*, bearing at its outer extremity the friction surface adapted to bear against ring *e*, said piece *g* extending inwardly toward the center of the shaft and mounted in guideways in the flanges *p p'*, and to provided with collar *q*, the spring *n*, inter-

posed between flange *p* and collar *q*, the lever *j*, fulcrumed to the collar *d* at one end and provided with a cam-surface, *k*, the shifter *m*, and the link *l*, connecting the shifter with the free end of the lever *j*, all substantially as described. 15

ERSKINE L. BABCOCK.

Correction in Letters Patent No. 373,425.

It is hereby certified that the name of the assignee in Letters Patent No. 373,425, granted November 22, 1887, upon the application of Erskine L. Babcock, of Cuyahoga Falls, Ohio, for an improvement in "Clutches," was erroneously printed at the head of the specification the "Falls River Company," that said name should have been printed the *Falls Rivet Company*; and that said Letters Patent should be read with this correction therein that the same may conform to the record of the case in the Patent Office.

Signed, countersigned, and sealed this 29th day of November, A. D. 1887.

[SEAL.]

D. L. HAWKINS,
Acting Secretary of the Interior.
